SECURITY ALARM SYSTEM WITH REMOTELY OPERATIVE TEST CIRCUIT

Kenneth H. Schmidt, Danbury, Conn., assignor to Mosler Research Products, Inc., Danbury, Conn., a corporation of Delaware

Filed July 10, 1957, Ser. No. 670,998

7 Claims. (Cl. 340—214)

My invention relates broadly to security alarm systems, and more particularly to a testing circuit for remotely checking the condition of operation of such systems.

This invention pertains to security alarm systems of the class set forth in my copending application Serial No. 670,999 filed July 10, 1957, for Security Alarm System.

One of the objects of my invention is to provide a security alarm system with a built-in test circuit for checking the operation of the system.

Another object of my invention is to provide a test circuit for security alarm systems which enables an operator at a remote location to test the operation of the system in the protected area which is remotely removed from a guard station.

A further object of my invention is to provide a test circuit for security alarm systems which simulates the presence of an intruder in the protected area for operating the system in similitude for indicating whether or not the system is operating in protective condition.

Other and further objects of my invention are set forth more fully in the specification hereinafter following by reference to the accompanying drawings, in which:

Fig. 1 is a schematic view showing a typical installation protected by the security alarm system of my invention; and

Fig. 2 is a circuit diagram schematically showing the application of my invention to a transistorized capacity-responsive alarm system and illustrating the remotely operative test circuit of my invention.

My invention is directed to the construction of an electronic security alarm system in which the objects under protection are connected in series, and form an antenna system, and in which a test circuit is associated with this antenna system in such a way as to simulate the presence of an intruder in the protected area when the test circuit is energized. The test circuit is operated from a remotely located guard station so that the guard at that station can determine if the security system is operating effectively.

The system operates on an electromagnetic principle. A transistor oscillator, by means of the resonant antenna system, radiates radio frequency (RF) energy into the area surrounding the antenna system, thus setting up an electromagnetic field of stored RF energy.

An ultra-sensitive alarm relay circuit connected to the antenna resonating circuit through a detector circuit is balanced for the particular antenna system which has a test circuit member associated with it. The presence of any additional body or object in the electromagnetic field will upset the balance of the alarm relay circuit, thus sending in an alarm, since the amount of RF energy stored in the field and the capacity of the field has been changed. To simulate an additional body in the electromagnetic field the test circuit member, which is associated with and balanced in the antenna system, is grounded by a remotely operative relay, thus inserting a grounded object within the electromagnetic field and changing the capacity of the field. The result is that the alarm indica-

tors are energized through a relay controlled by the balanced alarm relay. The balanced alarm relay is of the self-resetting type so that the alarm indicators are deenergized when the test circuit is deenergized.

5 In referring to the figures in more detail, similar numerals refer to similar components throughout this specification.

In Fig. 1 I have shown a schematic view of a typical installation of the capacitance responsive alarm system 10 of my invention. It is comprised of: cabinet 1, which houses the oscillator, antenna tuning, detection, alarm activating, and test circuits along with the Day-Night or Off-On switch, and a battery for a self-contained power source; the antenna system, which consists of cabinet 15 housing 1, file cabinet 2 and safe 3 electrically connected by conductor 4 and electrically connected to the antenna tuning circuit in cabinet 1 by antenna connecting coaxial lead 5; and alarm indicator housing 6 which contains the alarm indicators, such as a buzzer and a light, alarm 20 silencer switch, system test switch, and a battery as a self-contained power source for the alarm indicators. The alarm indicator housing 6 is connected to cabinet 1 by conductors running through connecting conduit 7. Safe 3, file cabinet 2, and cabinet 1, of the antenna system, 25 are insulated from ground by insulating blocks 8. Grounding conductor 9, insulated from cabinet 1, supplies the grounding requirements for the system.

In Fig. 2 I have shown the electrical schematic diagram of the transistorized capacity alarm system 30 incorporating the system test circuit of my invention. Power source 10, an independent battery power source contained within cabinet housing 1, energizes the transistor-oscillator circuit through Day-Night switch 11, power buss 12, oscillator transformer primary winding 13, and base bias 35 resistor 14. Oscillator tank capacitance 15 and secondary winding 16 of the oscillator transformer form the tank circuit for the oscillator circuit and determine the radio frequency (RF) output of the oscillator circuit. The tank circuit is coupled to type NPN oscillator transistor 17a through oscillator transformer primary winding 13 and coupling capacitor 18. By-pass capacitor 19 is connected between power buss 12 and ground to remove any A.C. pickup from said power buss. The RF output from the oscillator transistor base 17b is coupled through coupling capacitor 20 and conductor 24 to the antenna tuning circuit which consists of tuning capacitor 21 in parallel with tapped primary winding 22 of detector transformer 23. The antenna system which consists of electrically conductive housing 1 coupled by means of desensitizing capacitor 25, and objects 26 to be protected (example: file cabinet 2 and safe 3 in Fig. 1) connected by means of antenna connecting coaxial lead 5, to internal antenna connecting conductor 5' which is connected to a tap on detector transformer tapped primary winding 22. The detector circuit contains detection transistor 27, which is 45 a type NPN transistor, the base 28a of which is connected to secondary winding 29 of detector transformer 23, thus inductively coupling the detector circuit to the balanced antenna system. Transistor collector member 28b is connected to power buss 12 and emitter member 50 28c is connected to ground buss 9' through tuning meter 30. The output of the detector circuit, from emitter member 28c, is connected to ground through by-pass capacitor 31 and to coil 32 of balanced alarm relay 33 through compensation coupling capacitor 34. For a more 55 thorough explanation of the basic theory of operation of the preceding circuit, refer to my copending application Serial No. 670,999, filed July 10, 1957, for Security Alarm System.

Balanced alarm relay 33 responds to very slight changes 60 in current of the magnitude of two micro-amperes and is of the self-resetting type. Movable contact arm 35

65

is connected to ground buss 9' and both relay contact points 36 are normally open and connected together.

The circuit of slave relay 37 consists of slave relay coil 38 and voltage drop resistor 39 connected in series across ground buss 9' and power buss 12, respectively. This necessarily puts slave relay 37 in a normally energized state when switch 11 is in the Night position. Alarm relay common contact points 36 are connected between the junction of voltage drop resistor 39 and slave relay coil 38. With this circuitry, whenever the balance of the alarm relay circuit is disturbed, the relay is energized and movable contact arm 40 grounds one of common contact points 36 which puts a ground on both ends of slave relay coil 38, thus deenergizing the normally energized slave relay 37. This causes slave relay contact arm 40 to move from the normally closed contact point 41 to the normally open contact point 42, thus activating an alarm remotely located in alarm indicator housing 6. Cabinet 1 also contains test relay 43 and test member or coil 45 disposed around, but not in contact with, internal antenna connecting conductor 5'. One end of test coil 45 is an open circuit. That is to say, the coil or member 45 is spatially related to the internal antenna conductor 5'. The other end of test coil 45 is connected to test relay movable contact member 46 which is in contact with open relay fixed contact point or stop 47 when the test relay is in the deenergized state. Normally open test relay fixed contact point 48 is connected to ground buss 9'. Connecting conductors 49 and 50 disposed in conduit 7 connect test relay coil 44 through test switch 51 to relay activating power source 52. Test switch 51 and power source 52, which may be a battery, are both remotely located in alarm indicator housing 6. When test switch 51 is thrown, test relay 43 is energized, moving test relay movable contact member 46 into contact with the grounded normally open test relay contact point 48. This connects open test coil 45 in a series circuit to ground which will change the current in the balanced alarm relay circuit since the balance of the antenna system has been disturbed and cause an alarm, since this grounded coil in proximity to the antenna system has added a small amount of capacity to the antenna in exactly the same manner as an intruder approaching a safe or file cabinet in the antenna system. With this testing arrangement an operator at the alarm housing 6 remotely located from the antenna system can test the system's operation without being in the immediate vicinity of the antenna system. Since the alarm relay is of the self-resetting type it will reset itself after the test switch 51 is returned to its normal position.

Alarm indicator housing 6 also contains indicator battery power source 58, and indicator light 53, and buzzer or audible alarm 54 connected in parallel. Indicator battery power source 58 is connected to slave relay movable contact arm member 41 by conductor 59 in conduit 7. The indicators are then activated by slave relay 37 when alarm relay 33 becomes unbalanced. Both indicators indicate when the system becomes unbalanced and goes into alarm since they are connected, by conductor 55 in conduit 7, to normally open slave relay contact 42. The buzzer or audible alarm 54 may be silenced by means of silencer switch 56 when the system is in an alarm condition, but the indicator light will not extinguish until the system is rebalanced and operating properly. For "fail-safe" protection, if the silencer switch has been thrown, it must be returned to the normal position when the system is rebalanced or the audible alarm indicator 54 will sound, since the silencer switch is wired to the normally closed contact point 41 of slave relay 37 by conductor 57.

Unauthorized opening of cabinet 1 is prevented while switch 11 is in the Night position since the cabinet housing is connected into the balanced antenna system. This being the case, if an intruder touched the cabinet he would change the amount of radio frequency energy stored in the antenna system field which would result in a current change in the balanced alarm relay circuit,

activating the relay and resulting in the alarm indicator being energized.

When switch 11 is in the Day position slave relay 37 is deenergized and slave relay movable contact member 41 is in contact with the normally open contact point 42. In this state, the alarm indicators are energized, so that during non-operating periods alarm silencer switch 56 must be moved to the normally open position, resulting in the audible alarm 54 being silenced. Visual indicator 53 will remain energized during non-operating periods.

To protect cabinet 1 from unauthorized opening during the Day periods of system non-operation, tamper switch 60 is disposed in alarm energizing conductor 59 and arranged to make contact between this line and conductor 57 if cabinet 1 is opened. Since silencer switch 56 is in the normally open position and thus connected to conductor 57, if cabinet 1 is opened a closed circuit between power source 58 and audible alarm 54 results and this alarm is energized while visual alarm 53 is deenergized.

Alarm indicator housing 6 is associated with tamper switch 61 to prevent any unauthorized opening of this housing during both operating and non-operating periods or during both Night and Day positions of switch 11. Tamper switch 61 is a double-pole, double-throw switch with both movable members mechanically associated with housing 6 and electrically connected to power source conductor 59.

Since slave relay movable contact member 40 may be in contact with either contact point 41 or 42 and thus in contact with connecting conductor 57 or 55, respectively, and silencer switch 56 may be in contact with either conductor 57 or 55, depending upon the operating state of the system, alarm housing tamper switch 61 is arranged so that any opening of housing 6 will move the tamper switch movable contact arms into contact with both conductors 57 and 55, thus putting B+ on both these conductors and energizing both alarm indicators independent of the positions of switches 11 and 56.

I desire that it be understood that my test circuit as herein set forth is equally applicable to both types of alarm systems of the classes as set forth in my copending applications Serial Number 671,013, filed July 10, 1957 for Electronic Barrier, and Serial Number 670,999, filed July 10, 1957, for Security Alarm System.

While I have described my invention in certain preferred embodiments, I realize that modifications may be made and I desire that it be understood that no limitations upon my invention are intended other than may be imposed by the scope of the appended claims.

What I claim as new and desire to secure by Letters Patent of the United States is as follows:

1. In a security alarm system, a power source, switching means connected with said power source, an oscillator circuit energized by said power source through said switching means, an antenna system, a circuit enclosing housing connected in said antenna system, an antenna connecting conductor, an antenna tuning circuit connected with said antenna system by said antenna connecting conductor, said antenna system and said circuit enclosing housing radiating an electromagnetic field, a detection circuit connected with said antenna system, a balanced alarm relay circuit connected with said detection circuit, a normally energized slave relay connected to said balanced alarm relay circuit, an alarm indicator, conductors connecting said alarm indicator with said normally energized slave relay, a test circuit coil, one end of said coil being open, said coil being disposed about said antenna connecting conductor, a test circuit relay having a movable contactor operating with respect to a fixed contact, and a series circuit including said contactor connected to the other end of said test circuit coil and contacting said fixed contact for connecting said coil to ground for simulating conditions of the approach of an intruder to said antenna system and operating said alarm indicator.
2. In a security alarm system as set forth in claim 1 in which said test circuit coil comprises a plurality of

electrically conductive turns insulated from said antenna connecting conductor and terminating in a free end immediately adjacent said antenna connecting conductor.

3. In a security alarm system, a circuit enclosing housing, a balanced antenna system, an oscillator circuit, said circuit enclosing housing connected in said balanced antenna system and both radiating an electromagnetic field when said oscillator circuit is energized, a detection circuit, a balanced alarm relay, a slave relay having a movable contactor and fixed contacts, said detection circuit coupled to said balanced antenna system and arranged to energize said balanced alarm relay, said slave relay connected in the output circuit of said balanced alarm relay and being in the normally energized state, an alarm indicator housing, an alarm indicator, an alarm silencing switch, an alarm indicator power means, said alarm indicator housing enclosing said alarm indicator, said alarm silencing switch and said alarm indicator power means, conductors connecting said movable contactor and said fixed contacts with said alarm indicator power means and said alarm indicator, said alarm silencing switch connected to said alarm indicator and movable between two of said connecting conductors, means coupled to said circuit enclosing housing and connected to said connecting conductors to energize said alarm indicator on the opening of said circuit enclosing housing when said oscillator circuit is deenergized, and means coupled to said alarm indicator housing and connected to said connecting conductors to energize said alarm indicator on the opening of said alarm indicator housing when said oscillator circuit is energized or deenergized.

4. In a security alarm system as set forth in claim 3, said means coupled to said alarm indicator housing and

connected to said connecting conductors being a double-pole-double-throw tamper switch operable on the opening of said housing.

5. In a security alarm system as set forth in claim 3, the said two connecting conductors between which the alarm silencing switch is movable being the conductors connecting said fixed contacts with said alarm indicator.

6. In a security alarm system as set forth in claim 3, in which said means coupled to said alarm indicator housing and connected to said connecting conductors is a tamper switch disposed in series with said alarm indicator power means and said conductor connected to said movable contactor and movable out of contact with said conductor connected to said movable contactor and into contact with said conductors connected to said fixed contact on the opening of said alarm indicator housing.

7. In a security alarm system as set forth in claim 3 in which said means coupled to said circuit enclosing housing and connected to said connecting conductors is a tamper switch disposed in series with said conductor connecting said movable contactor with said alarm indicator power means, being movable into contact with said conductor connecting said fixed contact which is normally energized to said alarm indicator on the opening of said circuit enclosing housing.
